UNITED STATES PATENT OFFICE.

CLARENCE L. CATHERMAN AND JOHN H. CATHERMAN, OF PORTER TOWNSHIP, CASS COUNTY, MICHIGAN.

CEMENT POST.

SPECIFICATION forming part of Letters Patent No. 768,112, dated August 23, 1904.

Application filed March 28, 1904. Serial No. 200,451. (No model.)

To all whom it may concern:

Be it known that we, CLARENCE L. CATHERMAN and JOHN H. CATHERMAN, citizens of the United States, residing in Porter township, in the county of Cass and State of Michigan, have invented certain new and useful Improvements in Cement Posts, of which the following is a specification, reference being had therein to the accompanying drawings.

10 Our invention relates to improvements in fence-posts or other columns made of cement, concrete, or the like, one of the objects being to provide a post of the class described wherein in simplicity and inexpensiveness of construction shall be combined with durability and strength.

15 A further object of the invention is to provide a post that shall have special reinforcements at the point where the most strain is usually encountered in cement posts or columns, and that is where the most resistance and tension is caused by the action of the frost in the soil where the post or column may be embedded.

20 25 A further object of our said invention is to provide for the use of barbed wire of the sort commonly known to commerce as a "reinforcing power" in the manufacture of plastic posts, and still another object is to provide 30 improved means for securing wire fencing to such posts.

25 The invention consists in the novel features and details of construction which will be hereinafter more fully set forth, illustrated, and 35 finally claimed.

30 In the drawings accompanying this specification and made a part hereof, Figure 1 is a perspective view of the post, showing the set of short cables embedded therein. Fig. 2 is a 40 detail view of one of the short cables. Fig. 3 is an elevation of the post, showing a portion of the runner-wires. Fig. 4 is a horizontal section.

45 In the drawings similar letters of reference designate corresponding parts throughout the several views.

A designates the body portion of a post or

column made of any plastic material, such as cement, concrete, and the like.

50 B is a single strand of wire bent on itself in the form of an inverted U and having at its lower ends projecting prongs or anchors a. This strand of wire is also provided with a plurality of barbs b, disposed at any suitable distance apart, being preferably equidistant 55 from each other. These barbs are preferable to all other forms for the purpose of lending tensile strength to the post. A plurality of these sections of barbed-wire strands B are placed in the post while the same is in its plastic 60 state and there allowed to remain in position until the material of which the post is made is permitted to harden for use. As many of the strands B may be placed in the post as are found desirable.

65 As a special means of lending strength and durability to this class of posts frost-resistors C are formed of short pieces or strands of wire bent at right angles at the ends thereof, thus forming prongs or anchors c. These 70 strands or pieces of wire are also embedded in the post while its material is yet in a plastic state at a point where they will reinforce the same at the soil-line. It will at once be observed that any desirable number of these 75 frost-resistors may be used and that they may be disposed at any suitable relation to each other.

80 D designates a preferred form of staple to be embedded in the post at suitable distances from each other. These staples are formed of a single strand of wire or other suitable material bent on itself in the shape of a U, then bent back again in the form of hooks at each end, as shown. These staples may be 85 placed in the post, as shown in Fig. 4, leaving an extended loop d. This form of staple is found to be preferable to any other on account of its simplicity of construction and the further reason that it cannot possibly be 90 pulled from the post without breaking the post. However, different modifications of form will suggest themselves to the skilled mechanic, and we do not, therefore, desire to

be limited to the precise construction shown. These staples may be arranged in the post, as shown in Fig. 3, the runner-wires E passing above a single staple, as shown at e, and a locking-rod F, passing through the projecting loop d to hold the runner-wires in place, or two of the staples may be embedded close to each other, as shown at f, leaving only sufficient space for the runner-wires E to pass 10 between them and the locking-rod, which passes through the extending loops d, as above described.

As a further means of lending tensile strength to this post a single strand of wire 15 G, having a plurality of barbs g thereon, arranged at frequent intervals and preferably equidistant from each other, may be placed in the center of the post, as shown.

While the reinforcing means herein shown 20 and described are shown and described as applicable to fence-posts, it is obvious that our invention can be applied to mile-posts, corner-stones, telegraph-poles, building-columns, or similar articles. It is also obvious 25 that the shape of the post or column is immaterial, since our invention can be applied to posts or columns of any geometrical figure or form desired.

Having thus described our said invention, 30 what we claim as new, and desire to secure by Letters Patent of the United States, is—

1. A composition fence-post having reinforcing-cables embedded therein near the outer corners, each extending longitudinally 35 thereof for approximately the full length of the post, laterally-extending anchors secured to the cables at intervals, another set of shorter cables embedded in the post within

the area inclosed by the first set and extending longitudinally from a point below to a point above the ground-line of the post. 40

2. A composition fence-post having reinforcing-cables embedded therein, each consisting of an inverted-U-shaped metal rod arranged with the arms substantially parallel 45 and occupying positions near the outer corners of the post, each of the arms bent inwardly at its end parallel to the side face of the post to constitute anchors, barbs secured to the cables at intervals, and another set of 50 shorter cables embedded in the post at the side of the center and within the area inclosed by the first set and extending longitudinally from a point below to a point above the ground-line of the post. 55

3. A composition fence-post having reinforcing-cables embedded therein near the outer corners, each consisting of barbed wire with the ends bent inwardly to constitute anchors, another cable extending longitudinally 60 of the central axis of the post and provided with barbs, and a third set of shorter cables of barbed wire having inturned ends and arranged longitudinally in the post within the area inclosed by the first set, the first two 65 sets of cables extending for approximately the full length of the post and the third set extending from a position below to a point above the ground-line.

In testimony whereof we hereunto affix our 70 signatures in presence of two witnesses.

CLARENCE L. CATHERMAN.
JOHN H. CATHERMAN.
